COMBINED DESK AND PHOTOCOPY APPARATUS

Eugene T. Bonk, Arlington Heights, and Quentin R. Sharp, Mount Prospect, Ill., assignors to Addressograph-Multigraph Corporation, Mount Prospect, Ill., a corporation of Delaware

Filed Oct. 20, 1965, Ser. No. 87,645

Term of patent 14 years

(Cl. D33—7)

Fig. 1.

Fig. 2.

Fig.3.

Fig.4.

Fig.5.

Fig.6.

FIGURE 1 is a perspective view showing the working side of the combined desk and photocopy apparatus showing our new design;

FIGURE 2 is a top plan view thereof;

FIGURE 3 is a front elevation thereof;

FIGURE 4 is a right side elevation thereof;

FIGURE 5 is a left side elevation thereof; and

FIGURE 6 is a rear elevation thereof; and

FIGURE 7 is an enlarged fragmentary view in perspective of the top corner portion of the desk.

The design is characterized by the top corner portion of the desk which is disclosed in greater detail in FIGURE 7.

We claim:

The ornamental design for a combined desk and photocopy apparatus, substantially as shown and described.
